DESIGN FOR A COMBINATION WATER AND ICE BAG OR SIMILAR ARTICLE

Raymond W. Albright, Akron, Ohio, assignor to
American Anode Inc., Akron, Ohio, a corpora-
tion of Delaware

Application October 31, 1940, Serial No. 96,242

Term of patent 14 years

To all whom it may concern:

Be it known that I, Raymond W. Albright, a citizen of the United States, residing at Akron, in the county of Summit and State of Ohio, have invented a new, original, and ornamental Design for a Combination Water and Ice Bag or Similar Article, of which the following is a specification, reference being had to the accompanying drawing forming a part thereof.

In the drawing,

Fig. 1 is a front elevational view of a combina-

tion water and ice bag or similar article embodying my new design;

Fig. 2 is a vertical section taken on line 2—2 of Fig. 1.

The back of the bag or similar article is substantially plain.

I claim:

The ornamental design for a combination water and ice bag or similar article, as shown and described.

RAYMOND W. ALBRIGHT.
